PRINTING TELEGRAPH APPARATUS

Alfred Edward Thompson and Reginald Dennis Salmon, Croydon, England, assignors to Creed and Company Limited, Croydon, Surrey, England

Application December 29, 1937, Serial No. 182,200
In Great Britain January 12, 1937

18 Claims. (Cl. 178—35)

This invention relates to a type printing telegraph receiver of the step by step type.

According to one feature of the invention we provide such a receiver in which the type wheel 5 is driven and the printing hammer actuated from a driving shaft rotated by a source of power through a coiled spring.

The actuations of the printing hammer may be controlled by the movement of the type wheel 10 shaft in such manner that the hammer is actuated when this shaft is at rest for longer than a predetermined time.

The nature of the invention will be better understood from the following description of one embodiment thereof taken in conjunction with the accompanying drawings in which:

Fig. 1 is a plan view with some parts shown in section;

Fig. 2 is a front elevation partly in section with certain parts omitted;

Fig. 3 is a side elevation from the left of Fig. 2; Figs. 3a and 3b show details of Fig. 3;

Fig. 4 is a section on the line B—B in Fig. 2;

Fig. 5 is a section on the line C—C or on the 25 line D—D of Fig. 4;

Figs. 6 and 7 show the printing hammer mechanism;

Figs. 8 and 9 show details of the synchronising mechanism for moving the type wheel into a 30 predetermined position;

Figs. 10, 11, 12 and 13 show details of a mechanism for indicating the tension in the coiled spring through which the apparatus is driven.

The embodiment illustrated in the drawings is 35 driven from a shaft 2 to which is affixed a handle 1 so that the shaft 2 may be turned by hand, but it is to be understood that this shaft 2 may be driven by an electric motor. The shaft 2 drives, by means of a worm wheel 4 fixed thereon a gear 40 wheel 3 mounted upon a drum 5. To the inner circumference of drum 5 is fixed one end of a coiled spring 6 the other end of which is attached to a shaft 7 mounted centrally of the drum 5. The shaft 7 is thus driven from the shaft 2 through tension applied to the coil spring 6.

Keyed to shaft 7 is an arm 20 carrying a planet wheel 16a which meshes with an inner sun wheel 15a, carried on a sleeve 19 within which shaft 7 is freely rotatable, and an outer sun wheel 14a. 50 The latter is in the form of a disc having teeth on its inner circumference. It is carried by a drum 21 mounted on a sleeve 22 about shaft 7. Attached to drum 21 is a gear wheel 23 which meshes with a gear wheel 24 fixed on a shaft 25. 55 On the shaft 25 is a gear wheel 26 meshing with

a gear 27 on a shaft 28 which also carries an escapement wheel 29. One end of a member 30 pivoted at 31 engages with the escapement wheel 29 and the other end of this member 30 is attached to the armature 32 of the receiving magnet. Thus the shaft 7 tends to drive the shaft 25 through planet wheel 16a, outer sun wheel 14a, drum 21, gears 23 and 24, but is normally prevented from doing so by engagement of member 30 with escapement 29 and this, through 10 gears 27 and 26 holds shaft 25 stationary. When the armature 32 moves from one position to the other in response to a line reversal, the escapement 29 is allowed to rotate for a quarter of a revolution and thus allows shaft 25 to rotate. 15 Shaft 25 drives, through an inner sun wheel 104 fixed thereon, planet wheel 105, and outer sun-wheel 106, a shaft 107 on which are fixed type wheels 24a and 24b. Planet wheel 105 is mounted on a sleeve 108 freely rotatable about 20 shaft 25 but is held stationary by means described later.

The sleeve 19 which carries the inner sun wheel 15a, also carries a gear wheel 33, which meshes with a gear wheel 34 on a shaft 35. The 25 shaft 35 carries at one end a cam wheel 36 for actuating the printing hammer and at the other end a detent cam 37 as shown in Fig. 3. This detent cam is normally held stationary by the engagement therewith of one end of a lever 38 30 pivoted at 39. The lever 38 tends to be drawn out of engagement with wheel 37 by a spring 40 but is held in engagement by the pressure thereon of a frame 41 pivoted at 42 and held against lever 38 by a spring 43. Slidably mounted in frame 41 35 is a rod 44 which is attached to a lever 45 pivoted on the same pivot pin 39. The lever 45 tends to be rotated in a clockwise direction in Fig. 3 by a spring 46 but is held by an arm 47 of a three armed lever, 47, 48, 49. The arm 47 contacts 40 with the rod 44 and prevents it from rising. This three armed lever is pivoted at 51, and a roller 52 carried by arm 48 is held against a cam 53 on shaft 28 by a spring 50. The third arm 49 is connected by a link 54 to a ratchet wheel 45 55.

When the shaft 28 is allowed to rotate on the receipt of impulses, the cam 53 throws the roller 52 away from it and so moves the lever 41, 48, 49 in a clockwise direction about its pivot. 50 The arm 49 rotates ratchet wheel 55 and the arm 47 moving to the left in Fig. 3 allows rod 44 to rise in front of the tip of the arm 47. The raising of rod 44 allows lever 45, to which it is attached, to move clockwise about its pivot 39, 55

but it is limited in its rotation by the engagement of its right hand end with the upper edge of lever 38. The roller 52 and arm 48 tend to return, under the action of spring 50 into each 5 hollow of the cam 53. This return is delayed by the mechanism shown in Fig. 3a. Pawls 56 and 57, mounted on gear wheel 58 and spring pressed into engagement with ratchet wheel 55, cause this gear wheel to rotate and through 10 suitable gearing, to drive escapement wheel 59, with which a watch type escapement pallet 60 engages. Thus whilst the shaft 28 is being allowed to rotate by received impulses the roller 52 cannot descend into the hollow of cam 53. 15 When the shaft 28 comes to rest, however, the roller 52 moves back into the hollow of cam 53 and the arm 47 in moving counterclockwise strikes the rod 44, tilts the frame 41 about its pivot, and so releases the lever 38 from engagement with detent cam 37. The detent cam thus allows shaft 35 to rotate. As soon as lever 38 releases detent cam 37, a roller 61 on the lever 38 comes into engagement with a resetting cam 62 also mounted on shaft 35. This cam 32 moves 20 the lever 38 so that it is moved back into the path of detent cam 37 beyond its normal position. Thus the lever 45 is also rotated so as to withdraw the rod 44 from engagement with the lever 47, thereby permitting the frame 41 to 25 return to its normal position under the influence of spring 43. The resetting cam 62 finally releases lever 38 so as to permit it to set back against frame 41 while still being held in the path of detent cam 37 at the end of one quarter 30 revolution. Shaft 35 is thus allowed to rotate 35 for a quarter of a revolution only.

When shaft 35 rotates, cam 36 (Fig. 6) thereon, which engages a projection 64 on the underside of a lever 70 strikes this lever upwards. 40 Lever 70 is secured to a lever 63 on the same pivot 65 and lever 63 is accordingly raised with it. Pivoted to lever 63 at 71 are two printing hammers 72 carrying two resilient pads 73 (of which one only is shown) which project into an 45 aperture 74 in lever 63. The paper strip passes under a curved guide 66 over aperture 74 and between feed rollers 68 and 69. The guide 66 is provided with a slot through which one of the pads 73 can press the paper strip against one 50 of the type wheels 24a or 24b when the lever 63 is jerked upwards by cam 36. Below the printing hammers 72 is a frame 121 running on a pin 122 and arranged so as to engage with one 55 or other of the two printing hammers. The frame is moved endways under the action of a three-armed lever 123, one arm of which engages with the frame 121 and the other two arms of which cooperate with arms 76 and 77 (Fig. 2) 60 on the typewheel spindle 107. The arrangement is such that when the printing hammer frame 63 is thrown upwards under the action of cam 36, one of the two printing hammers 72 is held by the frame 121 so as to strike the paper 65 against the typewheel, whereas the other printing hammer 72, which is not held, yields under the action of the interposing guard 66. If one of the arms 76 or 77 engages with the three-armed lever 123, the frame 121 will be moved endways; arm 76 thus causes the frame to move in one direction while arm 77 causes the frame to move in the other direction. These arms 76 and 77 are fixed to the type wheel shaft 25 in such manner that impulses representing the figure and letter shifts respectively place one or the other of 70 75

these cams to engage the lever 75 and move it and the guide 66 so that the slot in this guide comes below the appropriate type wheel.

The lever 63 carries a pawl 78 engaging a paper feed ratchet wheel 79, and on the return of lever 63, wheel 79 is rotated by one tooth to feed the paper strip forward. A retaining pawl 80 prevents return of the ratchet wheel 79.

In order to give an indication to the person turning the handle 1 of the tension being applied to the spring 6, a gear wheel 8 is attached to the drum 5 and drives through an idler gear 9 a gear wheel 10 on a shaft 11. Gear wheel 12 on shaft 11 meshes with a gear 13 mounted to rotate freely about shaft 1. Attached to gear 13 is an 15 outer sun wheel 14, similar to sun wheel 14a. A planet wheel 16 meshes between outer sun wheel 14 and inner sun wheel 15 secured to shaft 7. Planet wheel 16 is carried by a worm wheel 18 which rotates freely about shaft 7. Worm 20 wheel 18 meshes with a gear 84 on a shaft 82 which carries an indicator finger 81 moving over a scale 83. It will be seen that finger 81 only moves when there is relative movement between the inner sun wheel 15 driven by shaft 7 and 25 outer sun wheel 14 driven in reverse direction by the drum 5. If the person turning the handle 1 turns at such a rate that he keeps the finger 81 between two given points of the scale 83, most clearly seen in Fig. 13, he is turning at the correct rate. If a motor is used as the driving power such as shown at 181 in Fig. 13, the movement of finger 81 to a predetermined displacement may be made to open contacts 182 in the motor circuit. In this way the motor can be caused 30 to run only when finger 81 is maintained below a predetermined point on scale 83, so that a substantially constant tension on the spring may be maintained.

Since in a step by step printer an error in the 40 selection of one character on the type wheel leads to all subsequent characters being wrongly printed, it is necessary to provide some means for moving the type wheel into a predetermined initial 45 position.

According to a feature of this invention the receipt of a continuous series of a greater number of impulses than that required to rotate the type wheel through a complete revolution causes 50 the stoppage of the type wheel in a predetermined position.

As previously stated the planet wheel 105 forming part of the sun and planet gearing through which the type wheels 24a and 24b are driven 55 from shaft 25, is mounted on a sleeve 108 freely rotatable about shaft 25. Fixed to the sleeve 108 is a toothed disc 100, Fig. 9, which is held stationary by the engagement therewith of a detent 109 mounted on a lever 110. The lever 110 is 60 fixed to a lever 111 held in position by a spring 112 so that detent 109 is between two teeth of wheel 100. Mounted on shaft 107 is a gear wheel 86, which meshes with a larger gear wheel 85, Fig. 8, to which is fixed a gear wheel 87 meshing with a toothed segment 88, which rotates about an axis 113 mounted on a lever 98. Attached to lever 98 is a second lever 91 pivoted on the same pivot 114 and lever 91 carries a roller 93 and is under the influence of a spring 92 70 which holds roller 93 against a cam 94 on the shaft 35.

When the shaft 107 is rotated gear 86 drives, through gears 85 and 87, the segment 88 in a clockwise direction in Fig. 8. Each time that 75

shaft 35 is allowed to rotate through a quarter of a revolution to actuate the printing lever, roller 93 is thrown away from cam 94 and segment 88 is removed from engagement with gear wheel 87. It is thus returned to initial position by spring 89.

If, however, a greater number of impulses than is required to rotate the type wheel through one revolution is received, the segment 88 is rotated 5 until a pin 115 thereon engages a lever 101, turns it in a counterclockwise direction and disengages it from a lever 102. Lever 102 then turns until a nose 114 thereon engages a disc 103 (Figs. 1 and 9), fixed to the shaft 107. The 10 circumference of the disc 103 is formed with a notch 117 corresponding to a predetermined position of the type wheels 24a and 24b. As the shaft 107 continues to rotate the notch 117 comes 15 opposite the nose 116 of lever 102 and the lever 20 falls into the notch under the influence of spring 118. The lever 102 in turning moves lever 111 to remove the detent 109 from wheel 100. The type 25 wheel shaft is held stationary, and the further rotation of shaft 25 simply results in idle rotation of the planet wheel 105 and toothed wheel 100. As soon as the train of impulses ceases, 30 shaft 35 is allowed to rotate in the manner previously described and roller 93 is thrown away from cam 94. Segment 88 is disengaged from gear wheel 87 and returns to initial position. The 35 end 119 of lever 90 engages a projection 120 on lever 102 and removes the nose 116 from the notch 117. Lever 102 reengages with latch 101 and allows lever 111 to move so that the detent 40 109 reengages toothed wheel 100.

What is claimed is:

1. In a step-by-step telegraph receiver, a type wheel, means including a driving shaft for operating said type wheel, a printing hammer, a 40 printing shaft, a cam on said shaft, means for normally holding said cam against rotation and releasing it at the end of a train of impulses, and means under the joint control of said cam and driving shaft for actuating said printing 45 hammer.

2. The structure defined in claim 1, and differential gearing connecting said driving shaft with said type wheel and printing shaft.

3. The structure defined in claim 1, a planet 50 wheel rotated by said driving shaft, inner and outer sun wheels meshing with said planet wheel, one of said sun wheels driving said type wheel, and the other the printing shaft.

4. The structure defined in claim 1, an escapement wheel on said printing shaft, a detent 55 normally holding said escapement wheel from rotating, and means operative when the type wheel comes to rest for tripping said detent.

5. In a step-by-step telegraph receiver, a receiving magnet, a shaft, an escapement mechanism controlled by said magnet, means including said escapement mechanism for controlling the rotation of said shaft through a large fraction of a revolution at each actuation of said mechanism by said magnet, a type wheel and means for rotating said type wheel for the distance between two characters for each said large fraction of a revolution of said shaft.

6. The structure defined in claim 5, a type 70 wheel shaft, a gearing between said shaft and type wheel shaft, and a source of power normally coupled with said type wheel shaft.

7. In a step-by-step telegraph receiver, a first 75 shaft, means for rotating it, a second shaft, a train of gears comprising an intermediate gear

and connecting said shafts, an escapement mechanism normally holding said second shaft against rotation, a receiving magnet controlling said mechanism, and a type wheel controlled by said intermediate gear.

8. In a step-by-step telegraph receiver, a source of power, a first shaft rotated by said source of power, a second shaft, means including a coiled spring for rotating said second shaft under the control of said first shaft, a differential gear comprising gears driven respectively by said first and second shafts, and also an additional gear for controlling the tension of said coiled spring.

9. A step-by-step telegraph receiver as defined 15 in claim 8, further comprising a third shaft, a cam pointer attached thereto, means controlled by said additional gearing for rotating said third shaft, a circuit for operating said source of power, and means in said circuit controlled by said 20 cam for controlling operation of said power source.

10. In a step-by-step printing telegraph receiver, a type wheel, a wheel rotating with said type wheel, a lever, means for causing said lever rapidly to move away from said wheel and relatively slowly to return towards said wheel, a printing hammer, and means controlled by said lever during its relatively slow movement for automatically actuating said printing hammer.

11. The device defined in claim 10, and in which a rotatable shaft is provided for actuating said printing hammer, and a detent restraining movement of said shaft tripped by said lever during its relatively slow return movement.

12. The device defined in claim 10, a ratchet wheel actuated by said lever, a pawl under which said ratchet wheel rides when the lever is moved in one direction and which is engaged by the ratchet wheel when the lever is moved in the opposite direction, and a gear wheel rotated by said ratchet wheel when it engages said pawl.

13. In a step-by-step telegraph receiver, a lever, a type wheel, means for rotating said type wheel step-by-step, means for moving said lever rapidly in one direction on each step of rotation of said type wheel, means for moving said lever relatively slowly in the opposite direction, a printing hammer, and means for actuating said printing hammer when said lever moves a predetermined distance during its movement in said opposite direction.

14. The device defined in claim 13, and a trip member, means for releasing said trip member during the first mentioned ratchet movement of 55 said lever and engaged by said lever during its second mentioned relatively slow movement, and means for actuating the printing hammer by said trip member.

15. The device according to claim 13 in which 60 the printing hammer is actuated by means of a cam, a trip member, means for releasing said trip member during the first mentioned rapid movement of the lever, means for engaging said trip member by the lever during the second mentioned relatively slow movement, and a detent controlled by said trip member for releasing said cam for a limited motion.

16. In a step-by-step telegraph receiver, two type wheels, a printing hammer, and means controlled by said printing hammer operable in certain positions of each type wheel for moving the other type wheel into printing position.

17. In a step-by-step telegraph receiver, means for receiving trains of impulses, a type wheel, 75

and means responsive to a train of more than a predetermined number of impulses for positioning the type wheel in a predetermined position.

5 18. The device defined in claim 17, a differential gearing for driving said type wheel, means responsive to the receipt of more than the prede-

termined number of impulses for holding said type wheel stationary, and means for rotating said gear idly in response to impulses in excess of said predetermined number.

ALFRED EDWARD THOMPSON.
REGINALD DENNIS SALMON.
